US0D1049806S

(12) **United States Design Patent** (10) **Patent No.:** **US D1,049,806 S**
Pieper et al. (45) **Date of Patent:** **** Nov. 5, 2024**

(54) **SHOVEL**

- (71) Applicant: **Allsop, Inc.**, Bellingham, WA (US)
(72) Inventors: **Susan Pieper**, Salt Lake City, UT (US);
Travis Dean, Salt Lake City, UT (US)
(73) Assignee: **Allsop, Inc.**, Bellingham, WA (US)
(**) Term: **15 Years**

(21) Appl. No.: **29/847,111**(22) Filed: **Jul. 21, 2022**

(51) **LOC (14) Cl.** **08-01**
(52) **U.S. Cl.** **D8/10**
USPC **D8/10**

(58) **Field of Classification Search**

USPC D8/1, 7, 8, 9, 10, 88, 98; D15/11, 25,
D15/26, 28; D21/532; D30/162
CPC .. A01B 1/02; A01B 1/022; A01B 1/08; A01B
1/222; A01G 3/06

Primary Examiner — Jack Reickel*Assistant Examiner* — Sydney M Evans(74) *Attorney, Agent, or Firm* — Eric B. Fugett; Mark A. Pitchford; Pitchford Fugett, PLLC(57) **CLAIM**

The ornamental design for a shovel as shown and described.

DESCRIPTION

FIG. 1 is a perspective view of a first embodiment of the claimed design;

FIG. 2 is a right side view of the first embodiment;

FIG. 3 is a left side view of the first embodiment;

FIG. 4 is a top view of the first embodiment;

FIG. 5 is a bottom side view of the first embodiment;

FIG. 6 is a front view of the first embodiment;

FIG. 7 is a back view of the first embodiment;

FIG. 8 is a perspective view of a second embodiment of the claimed design;

FIG. 9 is a right side view of the second embodiment;

FIG. 10 is a left side view of the second embodiment;

FIG. 11 is a top view of the second embodiment;

FIG. 12 is a bottom side view of the second embodiment;

FIG. 13 is a front view of the second embodiment; and,

FIG. 14 is a back view of the second embodiment.
